UNITED STATES PATENT OFFICE.

JOHN WIECHMANN, OF ALBANY, NEW YORK.

BOILER-TUBE CLEANER.

982,652.

Specification of Letters Patent. Patented Jan. 24, 1911.

Application filed January 27, 1909, Serial No. 474,605. Renewed August 1, 1910. Serial No. 574,994.

To all whom it may concern:

Be it known that I, JOHN WIECHMANN, a citizen of the United States, and a resident of Albany, in the county of Albany and 5 State of New York, have invented a new and Improved Boiler-Tube Cleaner, of which the following is a full, clear, and exact description.

The invention relates to boiler tube cleaners having a motor for rotating the cleaner head.

The object of the invention is to provide a new and improved boiler tube cleaner, designed for thoroughly removing the scale 15 or other incrustation on the outer or on the inner surface of the boiler tube, the cleaner having a rotating hammer head for use within the tube, to loosen the incrustation by blows in rapid succession.

20 A practical embodiment of the invention is represented in the accompanying drawings forming a part of this specification, in which similar characters of reference indicate corresponding parts in all the views.

25 Figure 1 is a side elevation of the improvement as applied to the inside of the tube of a boiler, for loosening the incrustation on the outside of the tube, the latter being shown in section; Fig. 2 is a cross section of the same, on the line 2—2 of Fig. 1; Fig. 3 is a face view of a modified form of hammer head for removing the incrustation on the inside of a tube; and Fig. 4 is a side elevation of the same.

30 The head of the boiler tube cleaner is connected with and actuated by a motor A of any approved construction, preferably, however, of the turbine type, such for instance as shown and described in the application 35 for Letters Patent of the United States, No. 433,696, filed by me May 19, 1908, so that further description of this motor is not deemed necessary.

40 The shaft B of the motor A is connected 45 by a universal joint C with one end of the hammer head shaft D extending lengthwise within the tube E and carrying a hammer F, preferably in the shape of a star, and mounted loosely and concentrically on the shaft D, on opposite sides are weights G, secured to the shaft D by pins G' or other fastening means, the said weights extending eccentrically of the shaft D, as plainly illustrated in Figs. 1 and 2. Now when the tube cleaner 50 is passed into the tube E and the motor A is running, then a rotary motion is given to

the shaft D, and by the weights G the shaft is caused to swing outward in the direction of the weights, so that the points of the star-shaped hammer head F come successively in contact with the inner surface of the tube E, thus delivering blows against the said tube in rapid succession, thereby loosening the scale which may be on the outside 60 of the tube E or on the inside thereof. 65

It will be understood that by using a hammer head F with four points, for instance, and running the motor A at the rate of two thousand revolutions per minute, it is evident that the hammer head F delivers eight 70 thousand blows to the inside of the tube E per minute, and consequently the scale is readily loosened whether the scale is on the outside or the inside of the tube E.

When the scale is on the outside of the 75 tube E the concussion tends to loosen the scale, and when the scale is on the inside of the tube E use is preferably made of a hammer head F such as shown in Figs. 3 and 4, and having preferably more points, say six 80 or eight, each point being beveled to form a cutting edge, as indicated in said Figs. 3 and 4. Thus the hammer head shown in Figs. 3 and 4 not only delivers blows but also cuts into the scale, to insure quick loosening and removal thereof, it being understood that the scale is washed out of the tube E by the water discharged from the turbine motor A. 85

The boiler tube cleaner shown and described is very simple and durable in construction, composed of comparatively few parts, and not liable easily to get out of order.

Having thus described my invention, I 95 claim as new and desire to secure by Letters Patent:

1. In a rotary tube cleaner, the combination with a driving shaft, and cleaner head, of a universal coupling uniting said shaft and head, said head being weighted on one side of its axis, substantially as described. 100

2. A boiler tube cleaner comprising a motor, a shaft having a universal joint connection with the said motor, a hammer head secured concentrically on the said shaft, and a weight secured eccentrically on the shaft. 105

3. A boiler tube cleaner comprising a motor, a shaft having a universal joint connection with the said motor, a star-shaped hammer head mounted loosely and concentrically on the said shaft, and a weight secured fixedly and eccentrically on the said shaft. 110

4. A boiler tube cleaner comprising a motor, a shaft having a universal joint connection with the said motor, a star-shaped hammer head secured concentrically on the said shaft, and weights secured eccentrically on the said shaft, and on the opposite faces of the said hammer head.

In testimony whereof I have signed my name to this specification in the presence of two subscribing witnesses.

JOHN WIECHMANN.
